UNITED STATES PATENT OFFICE.

HENRY B. NEWHALL, OF PLAINFIELD, NEW JERSEY.

EXPANSION BOLT-ANCHOR.

No. 907,393.

Specification of Letters Patent.

Patented Dec. 22, 1908.

Application filed August 23, 1907. Serial No. 389,817.

To all whom it may concern:

Be it known that I, HENRY B. NEWHALL, a citizen of the United States, residing at Plainfield, in the county of Union and State of New Jersey, have invented certain new and useful Improvements in Expansion Bolt-Anchors, of which the following is a specification, taken in connection with the accompanying drawings.

10 This invention relates to expansion bolt anchors and more particularly to such anchors as will not mar or deface the support in which the anchor is mounted.

In the accompanying drawings, in which the same numerals refer to similar parts in the several figures, Figure 1 is a longitudinal vertical section taken through my improved bolt anchor and its support. Fig. 2 is a transverse vertical section on the line 2, 2 of Fig. 1 looking in the direction of the arrows. Fig. 3 is a perspective view of the bolt anchor, a part being broken away for the purpose of illustration. Fig. 4 is an end view of the bolt anchor. Fig. 5 is a longitudinal vertical section through a slightly modified form of bolt anchor similar to that illustrated in Figs. 1 and 3. Fig. 6 is an end elevation of a modified form of a bolt anchor formed in two parts. Fig. 7 is a side elevation of one of the two members forming the bolt anchor taken on the line 7, 7 of Fig. 6. Fig. 8 is a view similar to Fig. 7 showing the body portion screw-threaded.

In the illustrative embodiments of this invention shown in the drawings, 1 is a masonry or other support within which an opening 2 has been made for the reception of my bolt anchor 3. This anchor I make in two or more parts as 4 and 5, the body portion 4 being preferably formed cylindrical and made of some suitable non-yielding or non-bending metal, such, for instance, as cast or malleable iron. In the back 6 of the body portion 4 I preferably form one or more pockets 7, four being shown in Fig. 2, though it is to be understood that a greater or less number would fall within my invention. The lower portion 8 of these pockets is formed of greater diameter than the throat 9 to receive lugs 10 preferably formed integral with the tines or expansible members 11 which are shown as segments. In the form of the invention illustrated in Figs. 1 to 5 I use four tines 11, their respective lugs 10 co-operating each with the pockets 7 formed

in the cylindrical body portion 4, though it is to be understood, of course, that my invention is not limited to this or any other number. These expansible members or tines 11 I form of some material, preferably metal of less rigidity than the cylindrical body portion 4, so that they will yield readily to the action of the expanding means, such as, the screw 12 shown in Fig. 1, or the expansible means 13 shown in Fig. 5. These yielding members 11 may be formed of soft metal, such as lead or composition and I preferably form the lugs 10 by casting them directly within the pockets 8 in the body portion 4, though they may be placed within the pocket 7 in any other suitable manner.

After the bolt anchor is inserted within the aperture 2 of the support I expand the tines or expansible members 11 by screwing within them the expanding means 12. As shown in Fig. 1, this is in the form of a screw having a plain portion 31 which merely passes through the opening 14 in the body portion 4, the thread 15 upon the end of the screw 12 co-operating with the sides 16 of the tapering opening 17 cutting complementary screw threads in the tines or expansible members 11 and expanding them, as shown in Fig. 1 so that the entire bolt anchor 3 and the screw 12 are securely held within the socket 2. This expanding action of the members 11 takes place at a suitable distance from the face 18 of the support 1 and consequently the support is not marred or chipped, as there is practically no expanding force exerted upon the support 1 at that point, practically all such force being exerted by the expansible members or tines 11.

Instead of using an expansible means, such as 12, in Fig. 1, I may form screw threads, 95 which are preferably machine screw threads, 19 upon the interior of the cylindrical body portion 4 and use a co-operating expanding member which as shown in Fig. 5 is a screw 13 having at one end complementary machine screw threads 20 to co-operate with the machine screw threads 19 within the hollow portion of the body 4, the body 4 in this form of the invention acting as a nut for the screw. The other end 21 of the screw 13 is 100 formed tapering, as shown in Fig. 5, to co-operate with a tapering recess 22 formed by the tines or expansible members 11. In this form of my invention, the screw 13 is screwed within the body portion 4, the screw threads 110

coöoperating to give a powerful force to the inclined or wedged surface 21 to wedge or force axially the different expandible members 11; the expansion of the bolt anchor in this form as in the other form being substantially confined to the expandible members 11 which, as noted, are located at a sufficient distance within the aperture 2 of the support 1 to prevent marring or chipping of the face 18 of the support 1. I may also in some instances form the body portion 4 of my bolt anchor with an annular flange 30 which is adapted to limit the inward movement of a bolt anchor within the hole 2 by engaging with the surface 18 of the support 1. This annular flange 30 gives a neater appearance to the bolt anchor and also serves to protect the surface 18 which is that portion of the support 1 immediately adjacent to the opening 2. It is to be understood, however, that this flange may be omitted without departing from my invention.

My invention is also adapted for bolt anchors formed of two parts, such as shown in Figs. 6, 7 and 8. With the bolt anchor illustrated in Fig. 7 I use an expandible means such as the screw 12 shown in Fig. 1; with the form shown in Fig. 8 I use an expandible means such as a screw 13 in Fig. 5. In this form of the invention where the body portion 4 is made in two parts, 23 and 24, there is, of course, a slight tendency for the two members 23 and 24 to move away from each other, but this is so slight as to be inconsequential, and therefore a two-part bolt anchor, such as herein shown, formed of materials of different strength or resiliency will not mar or chip the face 18 of the support 1 when the expandible members 25 are made to grip the walls of the opening 2. Though I have described this expandible bolt as being formed of two metals of different strength or resiliency, it is to be distinctly understood that my bolt anchor is not limited to two different metals, for the body portion 4 or 23 may be of metal and the yielding members 11 and 25 of some non-metallic substance which would yield to pressure more readily than will the metal of which the body portions are formed. Furthermore, the entire bolt anchor may be made of two or more non-metallic substances, one of such substances being adapted to be relatively firm and the other or others being formed of material which would yield or bend more readily than the other material out of which the body portions would be made.

Having thus described this invention in connection with the illustrative embodiments thereof, to the details of which I do not desire to be limited, what is claimed as

new and what is desired to secure by Letters Patent is set forth in the appended claims.

1. An expansion bolt anchor formed of two separate connected parts, one of the parts being formed of relatively hard metal and the other of relatively soft metal.

2. An expansion bolt anchor having a body portion of relatively hard metal, one or more pockets formed in one surface of said member, another portion of the bolt anchor formed of relatively soft metal having connecting means located within one or more pockets of the relatively hard portion.

3. An expansion bolt anchor having a substantially cylindrical body portion formed of relatively hard metal, one or more tines or expandible members formed of relatively soft metal and means for connecting the tines to the body portion.

4. An expansion bolt anchor having a substantially hollow cylindrical body portion formed of relatively hard metal, screw threads formed in the interior of the body portion, one or more tines or expandible members formed of relatively soft metal, means for securing said members to the body portion, expanding means having screw threads in the interior of the body portion and a wedge surface to coöperate with the expandible members or tines to cause them to move axially.

5. An expansion bolt anchor formed of a plurality of connected parts of different materials, the material forming the face of the anchor being of greater resisting capacity than the other portion of the anchor.

6. An expansion bolt anchor formed of a plurality of connected parts of different metals, the metal forming the face of the anchor being of greater resisting capacity than the metal of the other portion of the anchor.

7. An expansion bolt anchor formed of two separate connected parts of different materials, one of the parts having greater resisting capacity than the other part.

8. An expansion bolt anchor having a substantially rigid portion of iron and an expandible portion formed of lead or one of its al. ys.

9. An expansion bolt anchor formed of two separate connected parts of different materials, one of the parts having greater resisting capacity than the other part, said parts being arranged end to end.
